COOKING STOVE.

No. 16,422.

Patented Dec. 15, 1885.

UNITED STATES PATENT OFFICE.

H. CLAY BASCOM, OF TROY, NEW YORK.

DESIGN FOR A COOKING-STOVE.

SPECIFICATION forming part of Design No. 16,422, dated December 15, 1885.

Application filed November 16, 1885. Serial No. 183,048. Term of patent 7 years.

To all whom it may concern:

Be it known that I, H. CLAY BASCOM, a citizen of the United States, residing in the city of Troy, in the county of Rensselaer and State of New York, have invented and produced a new and original Design for Cooking-Stoves, of which the following is a specification, reference being had to the accompanying engraving of a cooking-stove having said new design.

This design includes several new and separate distinctive parts and combinations of parts, as hereinafter specified, and shown in the aforesaid engraving.

15 One part is the ornamentation of the oven-door, consisting of the outer flower-branch ornament, B, and ornament C, and the central panel-plate, A, having the ornamental parts a, b, c, d, e, and f, substantially as shown.

20 Another part is the shape and ornamentation of the door or panel D, having five sides and the compound helix, leaf, and cornucopia ornament g.

25 Another part is the shape and ornamentation of the raised side panel, E, having the form shown, and the compound scroll-vine, leaflet, bar, and radiate ornament h.

The ornamentation of the side door, F, consists of the compound vine, leaf, and floret 30 ornament i and the compound helix and radiate ornament j.

The design for the side of the stove embraces the shape and ornamentation of the oven door, the doors D and F, and the panel 35 E, substantially as shown.

The design for the stove-front embraces the rearwardly-inclined and concavely-curved upper draft-door, G, and the door H, having the upper rearwardly-inclined and concavely-curved illumination portion k, the middle band part, l, and the lower concavely-curved and ornamented draft portion, m.

The design for the legs consists of the convexly-curved broad upper portion, n, having the compound ornament o, and the narrow 45 part p, having the flower-stem ornament q.

The whole design embraces the top, the side, including the oven-door and the parts D, E, and F, the front, the hearth, and the legs, shaped and ornamented so as to present substantially the appearance represented in the 50 engraving.

I claim as new--

1. In a design for a stove, the ornamentation of the oven-door, consisting of the border 55 ornaments, B and C, and the central ornamented panel-plate, A, as set forth.

2. In a design for a stove, the shape and ornamentation of the door or panel D, having five sides and the compound ornament g, as 60 shown.

3. In a design for a stove, the shape and ornamentation of the side panel, E, including the compound ornament h, as shown.

4. In a design for a stove, the ornamentation of the side door, F, consisting of the compound ornaments i and j, as set forth.

5. In a design for a stove, the shape and ornamentation of the side, embracing the oven-door and the doors or panels D E F, as set 70 forth.

6. In a design for a stove, the shape and ornamentation of the front, embracing the parts G and H k l m, as set forth.

7. In a design for a stove, the shape and ornamentation of the legs, consisting of the parts n o and p q, as set forth.

8. The design for a cooking-stove, embracing the top, the side, with its doors and panels, the front, the hearth, and the legs, shaped 80 and ornamented as set forth.

In testimony whereof I hereunto set my hand, in the presence of two subscribing witnesses, this 13th day of November, 1885.

H. CLAY BASCOM.
